ATTORNEY

UNITED STATES PATENT OFFICE.

EDWIN ROAT, OF BUFFALO, NEW YORK, ASSIGNOR OF ONE-HALF TO
HARRY HAMLIN, OF SAME PLACE.

APPARATUS FOR COOLING SIRUPS AND OTHER LIQUIDS.

SPECIFICATION forming part of Letters Patent No. 254,159, dated February 28, 1882.

Application filed December 14, 1881. (No model.)

To all whom it may concern:

Be it known that I, EDWIN ROAT, a citizen of the United States, residing at Buffalo, in the county of Erie and State of New York, have 5 invented certain new and useful Improvements in Apparatus for Cooling Sirups and other Liquids; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 The object of my invention is to facilitate the cooling of corn, cane, or other sirups which have been heated to a high temperature during the process of manufacture. The ordinary methods of cooling are slow, occasioning a loss 20 of valuable time in preparing the sirup for the market.

By my invention I am enabled to take sirup at a high temperature and in a comparatively short space of time so reduce its temperature 25 that it can be barreled with safety.

It consists substantially of a box or receiver divided into two compartments. The upper compartment is for the reception of the heated sirup. The lower compartment contains a system 30 of pipes into which cold water is introduced at the bottom, and passing through the pipes is conducted away at the top. The partition which divides the box into its two compartments is provided with slots or perforations 35 through which the heated sirup percolates upon the pipes below. The lower compartment is provided with outlets through which the cooled sirup is discharged into barrels, &c.

40 In the drawings, Figure 1 is a side elevation of my improved device, with a portion broken away to show the interior construction. Fig. 2 is a top plan view of the same, and Fig 3 is a transverse section taken on the line X X of 45 Fig. 2.

Referring to the drawings, $a\ a$ are the sides, $a'\ a'$ the ends, and $a^2\ a^2$ the two sloping sections of the bottom of the box cooler. The sides a are securely held in position upon the

vertical posts b by the tie-rods b' , which pass 50 through the posts b at the top and bottom, and are secured thereto by nuts. The interior of the box cooler is lined with sheet metal of any description, galvanized iron being preferred, and in the upper part thereof is placed 55 the trough or receptacle c , of material similar to the lining of the box, for the reception of the heated sirup. This trough rests upon bolts c' , which pass through the sides a of the box cooler, acting as braces for the box as well 60 as supports for the trough. The bottom of this trough is provided with slots or perforations c^2 , through which the sirup may pass into the compartment below. This lower compartment is filled with a system of pipes, d , arranged as 65 clearly shown in the figures of the drawings, through which cold water is passed from the bottom to the top.

By means of the horizontal connections d' and vertical connections d^2 the pipes of each 70 horizontal layer are joined, so as to form a continuous passage for the cold water, and each horizontal layer of pipes is connected with the layer above from bottom to top, so that the cold water entering from below at the point d^3 75 passes in a serpentine path through the lowest layer of pipe, and from there to the next layer above, and so on until it is discharged at the top through the outlet-pipe d^4 . The bottom of the cooler has the sloping sections $a^2\ a^2$, which 80 meet at the point a^3 , where the discharge-pipes $e\ e$ are located, through which the cooled sirup passes.

The heated sirup is discharged into the receptacle c from the pipe f , which has a regulating-valve located near its end, operated by a lever, f' , and float f^2 , by means of which the supply of sirup is regulated and controlled automatically.

The operation of my device is as follows: 90 The heated sirup is discharged from pipe f into the receptacle c in the top of the box cooler, the supply being regulated automatically by the valve and its operating lever and float. From thence it passes through the slots or perforations c^2 upon the pipes d in the space below. Cold water is kept running through these pipes from the bottom to the top, as has been 95

fully hereinbefore explained, and as the sirup drops down from pipe to pipe its heat is gradually extracted and carried off by reason of the contact with the cool surfaces of the pipes. By having the cold water enter from below I am enabled to pass the sirup over the coolest surface just as it is leaving the box cooler, thereby materially assisting in the rapid cooling of the sirup down to a temperature which will admit of immediate barreling.

My improved device is adapted for the cooling of liquids of any description, and by the substitution of hot water or steam for cold water could be utilized equally well in heating sirups or any other liquids.

I claim—

1. The box cooler consisting of the perforat-

ed trough or receptacle, and the system of pipes below such trough, through which cold water is passed from bottom to top, the whole being suitably inclosed, and operating substantially as shown and described.

2. In a box cooler, the combination of the perforated trough or receptacle, and the system of pipes through which a continuous stream of water can be passed from bottom to top, with an automatic device for regulating and controlling the supply of sirup to be cooled, substantially as shown and described.

EDWIN ROAT.
